UNITED STATES PATENT OFFICE.

FRANK E. JONES, OF KIRKWOOD, ILLINOIS.

DESIGN FOR A PAPER BOX.

SPECIFICATION forming part of Design No. 28,044, dated December 14, 1897.

Application filed October 16, 1897. Serial No. 655,484. Term of patent 3½ years.

To all whom it may concern:

Be it known that I, FRANK E. JONES, a citizen of the United States, residing at Kirkwood, in the county of Warren and State of Illinois, have invented and produced a new and original Design for a Paper Box, of which the following is a specification, reference being had to the accompanying drawings, forming part thereof.

10 In the drawings, Figure 1 is a view in perspective of a paper box, showing my new design. Fig. 2 is an end view thereof.

15 The leading feature of my design is a paper box shaped and ornamented to represent a bed.

20 The letter A designates the upper side, B and C the two sides, and D and E the two ends, of the box. The upperside A is slightly curved transversely and is ornamented on its outer surface with lines to represent the

pillows and bedclothing of the bed. The sides B and C are ornamented with lines to represent the sides and legs of the bedstead and the depending edge of the bed clothing or cover. The ends D and E are extended 25 upwardly above the plane of the upper side A to represent, respectively, the head and foot boards of the bedstead and are ornamented upon their outer and inner sides with lines to represent such head and foot boards 30 and also the legs of the bedstead.

I claim—

The design for a paper box substantially as herein shown and described.

In testimony whereof I affix my signature 35 in presence of two witnesses.

FRANK E. JONES.
